UNITED STATES PATENT OFFICE.

ALFRED H. HUMPHREY, OF NEW YORK, N. Y.

DESIGN FOR A LAMP-GLOBE.

48,379.

Specification for Design.

Patented Jan. 4, 1916.

Application filed October 29, 1915. Serial No. 58,714. Term of patent 3½ years.

To all whom it may concern:

Be it known that I, **ALFRED H. HUMPHREY**, a citizen of the United States, residing at 46 West Broadway, city of New York, in the county of New York, State of New York, have invented a new, original, and ornamental Design for a Lamp-Globe, of which the following is a specification, reference being had to the accompanying drawing, forming a part thereof.

The figure is a side elevation of a lamp globe showing my new design.

I claim:

The ornamental design for a lamp globe as shown.

ALFRED H. HUMPHREY.

Witnesses:

H. S. HUMPHREY,
J. P. CONROY.
